HENNING K. JOHNSON, OF MINNEAPOLIS, MINNESOTA.

NAIL-EXTRACTOR AND HAMMER.

1,261,399.

Specification of Letters Patent. Patented Apr. 2, 1918.

Application filed June 13, 1917. Serial No. 174,531.

To all whom it may concern:

Be it known that I, HENNING K. JOHNSON, a citizen of the United States residing at Minneapolis, in the county of Hennepin 5 and State of Minnesota, have invented certain new and useful Improvements in Nail-Extractors and Hammers, of which the following is a specification.

This invention relates to combination 10 tools, and more particularly to a combined nail-extractor and hammer; the primary object being to provide a tool for extracting nails when opening packing-boxes and the like, which may, in addition to its utility as 15 a nail extractor, be used as a hammer when the packing-box is being assembled or closed.

One of the principal objects of this invention is to provide an improved tool which 20 will have the hammer element so constructed and associated with the nail-extractor means as to cause the hammer element to have a function for assisting the action of the nail-extracting means in addition to its 25 function as a hammer.

Another object of the invention is to provide a tool of this character which will include a single casting to support the nail-extracting elements and form the hammer 30 element, the latter being so disposed as to coöperate with the extracting means when the latter is being used, and to be disposed in the most advantageous position for use as a hammer.

35 A further object of this invention is the provision of a nail-extractor and hammer which consists of comparatively few parts and is simple in construction, but durable and well adapted to withstand the rough 40 usage to which devices of this character are ordinarily subjected.

For a full description of the invention and the advantages and merits thereof, reference is to be had to the following description 45 and the accompanying drawings, wherein is illustrated the preferred form of my invention, in which:

Figure 1 is an elevation of the device showing it in use as a nail extractor, parts 50 being broken away to disclose the construction;

Fig. 2 is an opposite side elevation showing the position the device will assume when used as a hammer; and

55 Fig. 3 is an end elevation.

Referring to the drawings wherein is

illustrated the preferred form of my invention and in which like characters of reference indicate corresponding parts throughout the several views, the shank 1 is provided at one end with a handle 2 and at its opposite end with a claw 3. A foot piece or shoe 4 is pivotally mounted on the shank 1 adjacent the claw 3 and this shoe consists of a relatively narrow casting having a slot 5 60 formed therein through which the shank 1 is extended. Reinforcing lugs 6 are formed on opposite sides of the casting to give strength to the same at the point where the openings 7 are formed for the reception of 65 a pivot pin 8.

Near the slot 5, and at the end of the shoe opposite the tang 9, is an opening 11 for the reception of the shank 12 of a complementary extracting claw 13 the point of which is 75 disposed toward the claw 3 whereby the two claws 3 and 13 may coöperate to obtain a grip on the nail, as shown to advantage by Fig. 1 of the drawing.

For the purposes of this description, the 80 complementary claws will be designated as the main claw 3 and the accessory claw 13. In the proper operation of the device it is necessary to first firmly grip the handle and press downwardly on the main claw 3 until 85 the point of the claw is embedded beneath the head of the nail to be extracted. The handle is then pulled toward the operator and the accessory claw 13 will move into engagement with the head of the nail as 90 shown by Fig. 1 of the drawing, while the tang 9 acts as a fulcrum for the device whereby the nail may be removed. It is essential that some weight be applied to the accessory claw 13 and for this purpose 95 I have provided an arcuate extension 14 which, in addition to its use in connection with the claw, is also used as a hammer as will be presently described. This extension is integrally formed with the casting constituting the shoe 4 and the portion of this extension is cored out to form the opening 15 whereby the greatest bulk of the weight is at the solid end 16 of the extension, the latter also forming the hammer head. It 100 will be obvious that when the device is used as above described the weighted end of the extension will assist the claw 13 in its gripping action on the head of the nail. The claw 13, of course, is fixed in proper position by a set-screw 17'. It 105

Referring particularly to Fig. 2 of the

drawing wherein the device is shown in position when in use as a hammer, it will be noted that the striking surface 17 of the hammer is in a horizontal plane when the shank 1, which serves as a handle for the hammer, is disposed at a slight angle with respect to the plane of the striking surface 17. This particular construction is obtained by providing a certain curve in the extension 10 14 so that the greater portion of the weight of the casting from which the shoe is formed is directly over, the striking surfaces 17 when the hammer is brought into play when driving a nail. In other words the weight 15 is properly balanced so that the device has all the advantages of the ordinary nail hammer in addition to its function and utility as a nail extractor.

In order that the hammer portion may be 20 held rigidly when the device is used as a hammer, I have provided a locking sleeve 18 which consists of a rectangular casing mounted upon the shank 1 and freely slideable thereon. One side of the casing or 25 sleeve has a screw-threaded opening to receive the shank of the set-screw 19 which has a finger grip 20 whereby the set-screw may be easily manipulated. When used as a nail-extractor as shown in Fig. 1, the 30 sleeve is raised and held in raised position by the set screw 19 so that free pivotal movement of the nail-extracting means is permitted. When in use as a hammer the sleeve will be moved forwardly into engagement 35 with the shoe as shown by Fig. 2 of the drawing and held in this position by the set-screw so that the hammer portion will be rigidly held to the handle or shank to effect the proper use of the device as a hammer.

40 From the foregoing it will be observed that a very simple and durable nail extractor and hammer has been provided, the details of which embody the preferred form. I desire it to be understood, however, that 45 slight changes in the minor details of construction may be made without departing from the spirit of the invention or the scope of the claims hereunto appended.

I claim—

50 1. A tool of the character described comprising a shank having a claw fixed at its

end, a shoe pivotally connected to the shank near the said claw and having an arcuate tang projecting from one end and an arcuate extension projecting from the opposite 55 end, the end of the said extension being shaped to provide a hammer head, the same being disposed considerably beyond the adjacent end of the shoe to add weight to the latter, and a complementary claw carried 60 by the said adjacent end of the shoe.

2. A tool of the character described comprising a shank having a claw fixed at its end, a shoe pivotally connected to the shank near the said claw and having an arcuate 65 tang projecting from one end and an arcuate extension projecting from the opposite end, the end of the said extension being shaped to provide a hammer head, the same being disposed considerably beyond the adjacent 70 end of the shoe to add weight to the latter, and a complementary claw carried by the said adjacent end of the shoe, the said tang being curved in an arc opposite to the curve of the said extension whereby the end 75 of the latter will be disposed in a plane considerably above the said tang when the latter is in operative position.

3. In a tool of the character described, the combination of a pair of complementary 80 claws, a shank having one of the claws formed on its end, a shoe having the shank pivotally connected thereto adjacent the said claw, the other claw being adjustably fixed to the said shoe whereby pivotal 85 movement of the shoe will cause co-operation of the claws, a hammer element formed by the extension on the shoe and having a portion removed to provide a weighted end for assisting the fixedly mounted claw in its 90 co-operation with the other claw, and means mounted on the shank to be moved into engagement with the shoe and fixed for rigidly holding the shoe in immovable position for permitting use of the extension 95 as a hammer.

In testimony whereof I affix my signature in presence of two witnesses.

HENNING K. JOHNSON.
